UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed May 8, 1928. Serial No. 107,656.

My invention relates to a slicing machine and particularly to a slicing machine for slicing meat which shall be light, simple to manufacture, and easy to operate. One purpose is the provision of a slicing machine of the type described wherein the knife is entirely masked from the operator except along the arc of the knife where the slicing is effected. Another object is the provision of improved supporting and guiding means for the meat support. Another object is the provision of an improved gauge plate for controlling the thickness of the slice. Another object is the provision of improved grinding or sharpening means for the knife. Another object is the provision of improved adjustment means for the knife. Other objects will appear from time to time in the course of the specification and claims.

I illustrate my invention more or less diagrammatically in the accompanying drawings wherein—

Figure 1 is an end elevation with parts broken away;

Figure 2 is a plan view with parts in horizontal section;

Figure 3 is a front elevation with parts broken away;

Figure 4 is a section on the line 4—4 of Figure 2;

Figure 5 is a section on the line 5—5 of Figure 3;

Figure 6 is a section on the line 6—6 of Figure 3;

Figure 7 is a section on the line 7—7 of Figure 3; and

Figure 8 is a section on the line 8—8 of Figure 3.

Like parts are indicated by like symbols throughout the specification and drawings.

A generally indicates any suitable base frame or member provided for example with the anti-frictional and noise deadening studs or supports A¹.

Mounted on such base member is any suit-

able motor means herein shown as the motor B from which projects the motor shaft B¹ on which is the driving pulley B² adapted to engage and drive the belt B³, herein shown as of triangular cross-section to engage the inclined faced channel B⁴ on the pulley B².

C is a knife supporting sleeve mounted upon the base A and including the shield portion C¹. It will be understood that the shield portion is continuous with or extends to the motor housing B and forms part of the general upwardly projecting housing or frame member C¹.

Mounted within the sleeve portion C is an inner sleeve D in which are mounted the ball bearing tracks D¹ to support the balls D² opposed to the inner tracks D³ on the knife shaft D⁴. D⁵ are locking nuts whereby to secure the knife shaft and roller bearing assembly together, the shaft D⁴ being enlarged as at D⁶ to engage the inner forward ball track D³. D⁷ is a channel pulley mounted on the shaft D⁴ adapted to receive about it the belt B³.

E is a knife disc proper secured to the shaft assembly for example by the screw E¹ and additionally secured to the pulley D⁷ for example by the screws E³. The knife disc is shown as convex and is peripherally cut away or recessed on its hollow face, as at E⁴ to leave a peripheral portion E⁵ projecting somewhat forwardly from the face of the knife, the inner face of which is preferably, but not necessarily, cupped.

The sleeve C is apertured as at G, the aperture passing partially through the cylindrical interior of the sleeve. Mounted in such aperture is the locking pin G¹ cut away as at G² to permit the passage of the inner sleeve D. The outer end of the pin is screw threaded as at G³ to receive the lock nut G⁴ whereby the pin may be longitudinally moved to clamp the inclined faces of the cut away portion G² against the opposed surface of the sleeve D.

Referring to Figure 6, T is a sleeve mounted in the wall or frame member C² penetrated by a central cylindrical aperture T¹ or a end of which is open and the opposite end of which is in communication with a smaller aperture T² in which is slidably positioned a pusher member T³ with an inner expanded terminal portion T⁴. Mounted in the open end of the sleeve T is the bearing block T⁵ secured for example by the screw T⁶ and slideable in it is the grinder shaft T⁷ upon the outer end of which is mounted any suitable grinding member T⁸. T⁹ is a ball race mounted upon the shaft T⁷ and opposed to the opposite ball race member T¹⁰ and the bearing balls T¹¹. T¹² is a supporting member for the ball race T¹⁰ and T¹⁴ is a spiral spring compressed between it and the plug T⁶. The operator may exert, through the medium of pin T³, as much pressure upon the grinding element T⁸ against the knife as he may desire and as may be necessary to produce the desired rapidity of grinding.

Referring to Figure 7 the frame member C² is inwardly expanded to form the cylindrical sleeve V in which is mounted the bearing block V¹ which receives the shaft V² at one end of which is mounted the swaging, burnishing or spinning element V³. Mounted upon the opposite end of the shaft is the ball race V⁴ opposed to the ball race V⁵. V⁶ is a supporting member for the ball race V⁵ and between it and the plug V¹ is compressed the spiral spring V⁷. Screw threaded into the opposite end of the cylinder is the member V⁸ in which is screw threaded the screw member V⁹ controlled by the knurled thumb piece V¹⁰. It is highly important that the face E⁵ of the cutter be not injured by unskillful attempts to sharpen the cutter, and as the removal of material should be entirely by means of the grinding element T⁸, and as the element V³ should act merely to bring the grinder burr out into the cutting plate, either for utilization as the cutting edge or for removal by the grinding element, it is highly important that the amount of pressure to be exerted upon the grinder by the element V³ be beyond unskillful control. The force of the spring V⁷ is therefore carefully adjusted in the factory and it will be noted that no amount of manipulation of the screw V⁹ by the operator will permit an extra heavy application of the element V³ to the cutter.

Mounted on the forward face of the frame member C¹ is the fixed guard plate H which may be of any suitable material. At its left edge, as shown in Figure 3, it is arcuately cut away as at H¹, the arcuate portion penetrating or seating closely within the peripheral channel E⁴ of the knife E the axis of the knife being slightly tilted in a horizontal plane from perpendicularity to the plate, as shown in Figure 2 to bring the edge of the knife forward into the position shown in such

figure, generally in the plane of the guard plate H.

J is a frame or housing member upwardly projecting from the opposite end of the base A. Mounted for rotation therewith is the control shaft J¹ upon the inner end of which is the worm J². Such shaft is controlled by the external handle J³ provided with indicating symbols as at J⁴ aligned with the opposed pointing member J⁵.

Pivoted to the vertical rock shafts J⁶ J⁷ within the housing J are the levers or pairs of levers K, K¹, at the outer end of each pair of which are pivoted the blocks or strips K², to which are secured any suitable gauge plate K³, the surface of which may be slightly convex or bowed, to conform to the cutting edge of the knife E since the active cutting portion of the knife, due to the angle at which it is set, is not in a vertical plane but is slightly bowed forward. The right edge of said gauge plate K³, as shown in Figure 3, may be arcuately formed, as at K⁴, generally concentrically with the arcuate portion H¹ of the fixed guard plate. The distance separating the opposed edges is, as shown in Figure 2, sufficient to permit the penetration therebetween of the peripheral portion E⁵ of the knife E.

Secured to the rock shaft J⁶ is a segment worm gear K⁷ which meshes with and is driven by the worm J². A tension spring K⁸ is secured at one end to a lug K⁹ on the frame J and at its opposite end to one of the pivoted blocks or strips K². This spring serves to hold the teeth in the segment K⁷ in close contact with the opposed teeth of the worm J².

Coiled around the upper part of the rock shaft J⁶ is a heavy spring K¹⁰, which is held under compression against the under side of one of the bearing lugs K¹¹ by the collar K¹² which is secured to the rock shaft J⁶. The resulting friction acts as a brake, and tends to hold the gauge plate K³ in any position in which it may be set by the operation of the handle J⁸.

The support of the gauge plate by means of the parallel links K, K¹ not only provides for maintenance of parallelism of the active face of the gauge plate relative to the active face of the guard plate and relative to the line of movement of the carriage O, but also makes possible the gradual widening of the throat between the active edge of the cutter and the forward edge of the gauge plate as that throat is deepened to provide for thicker slices, thereby providing the necessary amount of clearance for the thicker slices. It will be readily understood that various well-known mechanical mountings for the gauge plate, by which parallelism throughout adjustment may be maintained, and by which the desired widening of the throat is attained as the throat is deepened, will

readily suggest themselves to the average mechanic.

5 K^s is any suitable top or lid member extending from end to end of the slicing machine and adapted to be secured for example by the screws K^s to the housing J and the housing or frame member C^1 .

10 L is any suitable receiving plate for receiving the material sliced by the knife and L^1 is any suitable control switch for controlling the current to the motor of the motor housing B .

15 M is a track herein shown as of circular cross-section mounted for example on the supports M^1 upwardly projecting from the opposite ends of the base A . The ends of the track are enclosed by the sheaths M^2 apertured to permit the penetration of the bolts or screws M^3 headed as at M^4 and upwardly 20 extending through the base A , the support members M^1 , the sheaths M^2 and into the ends of the track M . Aligned beneath the track M is any suitable slide or rail M^5 herein shown as of rectangular cross-section.

25 Mounted for movement along the track M and the rail M^5 is any suitable carriage or supporting member herein shown as including a body portion O and a meat engaging member O^1 . Such meat engaging member includes a broad face O^2 slightly inclined to the horizontal and a narrower face O^3 sharply inclined to the horizontal the two being generally perpendicular to each other. Downwardly depending from the body portion O is an arm or slide O^4 with a depending finger O^5 adapted to engage one side of the slide M^5 . Movably secured to it is the finger member O^6 in which is any suitable adjusting member herein shown as the screw O^7 controlled by the lock nut O^8 . O^9 are any suitable buffer members adapted to contact the posts M^1 at each end of the excursion of the carriage. O^{10} is any suitable handle for the manual movement of the carriage. O^{11} is a pin fixed to the finger O^5 and having an enlarged head which engages the slide or track M^5 . In the present device the portion of the material which is in proximity to the knife and which in any given operation is to be severed from the body portion to form the slice, is manually moved in a direction at an angle to the movement of the carriage so as to bring it into contact with the gauge and guard plates and into slicing relationship to the knife. Any suitable means for this purpose may be utilized. The carriage O is arranged to underlie and entirely to support the material being sliced.

30 In the construction P is a meat face plate or pusher provided with the pins P^1 P^1 which penetrate opposed holes in the meat table support O . The pusher P is provided with a handle P^2 and carries on its front face pins P^3 to engage the meat or other substance 35 being sliced.

It will be realized that whereas I have illustrated and described a practical and operative device that nevertheless many changes may be made without departing from the spirit of my invention, and I therefore wish my drawings and description to be taken as in a broad sense illustrative and diagrammatic rather than as limiting me to my precise showing.

30 The use and operation of my invention are 75 as follows:

I provide a generally vertical fixed guard plate, arcuately cut away to permit the penetration or the exposure of the rotary knife. The plane of the knife is tilted in order to bring the exposed edge generally into the plane or close to the plane of the forward face of the guard plate, the knife being hollowed or sunk in order to permit its peripheral portion E^5 to extend forwardly beyond the body of the knife. Generally aligned with the fixed guard plate H is the adjustable gauge plate K^3 controlled by the worm J^2 which in turn is controlled by rotation of the handle J^3 . The gauge plate may, if desired, 90 be slightly bowed to conform to the curvature of the exposed knife edge. I have shown a fixed finger J^6 on the housing opposed to the symbols J^4 on the handle, but obviously any other practical means for controlling or 95 indicating the necessary rotation of the worm may be employed. In response to rotation of the worm the link or lever K^1 is rotated and moves in unison with the gauge plate K^3 . The lever or link rotates necessarily in unison 100 with the link K , the two being of like length between pivot points, the gauge K^3 always lying in a plane parallel with the plane of the guard plate H . The material being cut is placed upon the carriage and is moved, 105 for the cutting excursion, from left to right, as shown in Figures 2 and 3. The thickness of the slice is determined by the position of the gauge plate K^3 , the slice passes through the aperture between the edge of the knife and the gauge plate K^3 and drops upon the receiving plate L , from which it may be manually removed. With the gauge plate K^3 supported as herein shown, as the plate is 110 moved backwardly from the cutting plane, in order to increase the thickness of the slice to be produced, the arcuate edge of the gauge plate draws readily away from the cutting edge, so that the throat between the gauge plate and the cutting edge is both deepened and widened, and, as the slice is thereby 115 thickened, a relatively greater space is provided, through which the thickened slice may easily pass. This double recessive movement is the necessary result of the employment of the mounting herein shown, but obviously other means may be employed in 120 order to impart to the gauge plate the combined rearward and lateral movement above described. An advantage of this disposition 125 130

rests in the fact that the thickness of the slice increases more readily than does the actual distance between the gauge plate and the plane of the knife and a smaller movement of the gauge plate is necessary.

As shown in Figures 2 and 8, the guard plate H is adjustable toward and away from the knife, for example by means of rotation of the threaded stud bolt Q screwed to the lugs Q¹ on the frame C² and secured by the screws Q² threaded into the stud bolt Q. The position of the plate H is preferably initially adjusted at the factory but further adjustment, if necessary, may easily be made by the operator. The knife shaft sleeve D being also longitudinally adjusted, it is possible easily and accurately to position knife and guard plate in the proper relation. The housing C¹ and the plate H between them entirely enclose the knife driving mechanism and the knife is exposed only along the cutting edge and only when the gauge plate is withdrawn. When the gauge plate is advanced forwardly to the position shown in full line in Figure 2 the entire edge of the knife is guarded or concealed.

Referring to the grinding member shown in Figures 6 and 7 the grinding member of Figure 6 is normally withdrawn from contact with the knife. A spiral spring T¹⁴ normally withdraws the shaft T⁷ and with it the grinder T⁸ from contact with the knife and opposes the inner end of the shaft to the member T², the excursion of such member being limited by the expanded member T⁴. In response to a positive pressure, for example of the thumb or finger, against the member T², the spiral spring T¹⁴ may be compressed and the grinder is thrust into contact with the knife edge. Thus the operator has full control of the actual grinding, and may thrust the grinder, with whatever pressure he wishes, against the rear face of the rotating knife edge.

On the contrary, the swaging or burnishing member V³ of Figure 7 is normally drawn against the opposite edge of the blade, the spiral spring V⁷ serving to draw the shaft V² to the left as shown in the figure. The tension exerted by the burnisher depends exclusively upon the tension of the spring V⁷ which is initially set at the factory and is beyond the control of the operator. The screw V⁹ may be positively set to hold the burnisher out of contact with the knife, but the sole choice opened to the operator is whether to permit the burnisher to engage the forward face of the blade or not, the sole function of the burnisher being to rub off or swage back the burr produced by the grinding element T⁸.

Note that the shaft or pin T⁷ is positioned within the periphery of the knife and the grinder T⁸ therefore contacts the knife at a point where the stone approaches the knife

edge as it revolves, the shaft T⁷ rotating in the same direction as the knife shaft. The burnishing shaft V² on the contrary, is positioned beyond the periphery of the knife and rotates in an opposite direction, the burnishing disc contacting the knife at a point where the disc leaves the knife's edge as it revolves.

In normal operation both grinders may be normally out of contact with the knife and when grinding is desired a rotation of the finger piece V¹⁰ or a positive pressure against the member T² will hold one or the other of the grinding elements in contact with the knife.

In order to minimize the waste of material I employ a holder or face plate P guided on the support O for example by the pins P¹.

I claim:

1. In a slicing machine, a guard plate, a rotary knife positioned on one side of said plate and means for driving it, a gauge plate and means for moving it toward and away from the plane of the guard plate, while holding it continually in a plane parallel with such guard plate, comprising a plurality of pivoted arms of uniform length mounted upon such slicing machine and in rotatable relation with such gauge plate, and means for rotating them and means for holding said gauge plate in adjusted position.

2. In a slicing machine, a guard plate, a rotary knife positioned on one side of said plate and means for driving it, a gauge plate and means for moving it toward and away from the plane of the guard plate, while holding it continually in a plane parallel with such guard plate, comprising a plurality of pivoted arms of uniform length mounted upon such slicing machine and in rotatable relation with such gauge plate, and means for rotating them, comprising in part a gear associated with one of said arms, a worm in mesh therewith, and actuating means for rotating such worm.

3. In a slicing machine, a guard plate, a rotary knife positioned on one side of said plate and means for driving it, a gauge plate and means for moving it toward and away from the plane of the guard plate, comprising a plurality of pivoted arms of uniform length mounted upon such slicing machine and in rotatable relation with such gauge plate, and means for rotating them, comprising in part a gear associated with one of said arms, a worm in mesh therewith, and actuating means for rotating such worm, comprising a handle, and an indicating means for indicating the extent of the movement of the gauge plate, including a plurality of indicating symbols and a pointer, adapted for relative movement in response to movement of such handle.

4. In a slicing machine, a guard plate, a rotary knife positioned at one side of said

- guard plate, and means for driving it, a carrier mounted at the opposite side of the guard plate, and means for guiding it along a path parallel to the face thereof, a single supporting track for said carrier comprising a bar of generally circular cross-section, and means for preventing the rotation of said carrier about said bar, comprising a guide rail positioned beneath said bar and means, adjustable in relation to the width of said rail, depending from said carrier and engaging said rail. 5
5. The combination with a carriage for use with a slicing machine of a meat end plate mounted for longitudinal movement along said carriage, and a guiding member upon said end plate adapted to penetrate said carriage. 15
6. The combination with a carriage for use with a slicing machine of a meat end plate mounted for manual longitudinal movement along said carriage, a plurality of guiding members upon said end plate adapted to penetrate said carriage and to guide the travel of the meat end plate therealong. 20
7. The combination with a carriage for use with a slicing machine of a meat end plate mounted for manual longitudinal movement along said carriage, a plurality of guiding members upon said end plate adapted to penetrate said carriage and to guide the travel of the meat end plate therealong, and a handle upon said end plate and a plurality of meat engaging pins on the forward face thereof. 25
8. In a slicing machine, a rotary knife, a carrier, and means for guiding said carrier along a path across the face of said knife, including a pair of superposed vertically aligned tracks, and means for laterally adjusting said carrier in relation to one of said tracks. 40
9. In a slicing machine, a rotary knife, a carrier, and means for guiding said carrier along a path across the face of said knife, including a pair of superposed vertically aligned tracks, said carrier being rotatable, for adjustment, about one of said tracks, and means for laterally adjusting it in relation to the other. 45
10. In a slicing machine, a rotary knife, a carrier, and means for guiding said carrier along a path across the face of said knife, including a pair of superposed tracks, and means for laterally adjusting said carrier in relation to one of said tracks. 50
11. In a slicing machine, a rotary knife, a carrier and means for guiding said carrier along a path across the face of said knife, and means for angularly adjusting the plane described by the forward face of said carrier as it moves along said path, comprising a pair of generally parallel supporting tracks, the carrier being rotatable, for adjustment, about one of them, and means for adjusting it in relation to the other. 55
12. In a slicing machine, a rotary knife, a carrier and means for guiding said carrier along a path across the face of said knife, a face plate upon said carrier and a supporting structure therefor, and means for moving it toward and away from the knife along an axis generally perpendicular to the path of movement of the carrier, and guiding means therefor, including a plurality of pins. 70
13. In a slicing machine, a rotary knife, a carrier and means for guiding said carrier along a path across the face of said knife, a face plate upon said carrier and a supporting structure therefor, and means for moving it toward and away from the knife along an axis generally perpendicular to the path of movement of the carrier, and guiding means therefor, including a plurality of pins associated with said face plate structure. 80
14. In a slicing machine, a rotary knife and means for rotating it, the axis of rotation of said knife lying in a generally horizontal plane, a guard plate positioned forwardly of said knife and lying in a generally vertical plane, a gauge plate positioned in a plane generally parallel with the plane of said guard plate, a carriage adapted to support the material being sliced, and means for guiding said carriage along a path generally parallel with the faces of the gauge plate and the guard plate, and means for manually moving the material being sliced toward the gauge plate, including a pusher plate mounted upon the carriage, and lying in a plane parallel with the plane of the gauge plate, and means for guiding it along a path generally perpendicular to the plane of the gauge plate, and means for moving the material and carriage past the cutting edge of the knife. 95
15. In a manual feed slicing machine, a rotary knife, a motor for rotating it, a normally stationary and generally vertical guard plate for said knife, a generally vertical gauge plate positioned in a plane generally parallel with the plane of said guard plate, a carriage adapted to underlie and entirely to support the material being sliced and means for manually moving the portion of the material which is to be severed by the knife to form the slice, in a direction at an angle to the movement of the carriage and towards the gauge and guard plates and into slicing relationship to the knife, the guard plate being on the carriage side of the knife, and means for guiding said carriage along a path generally parallel with the faces of the gauge plate and guard plate. 110
16. In a slicing machine, a rotary knife, a carrier and means for guiding said carrier along a path across the face of the knife, including a pair of tracks one below the other and vertically aligned, and means for adjust- 120
17. In a slicing machine, a rotary knife, a carrier and means for guiding said carrier along a path across the face of the knife, including a pair of tracks one below the other and vertically aligned, and means for adjust- 125
18. In a slicing machine, a rotary knife, a carrier and means for guiding said carrier along a path across the face of the knife, including a pair of tracks one below the other and vertically aligned, and means for adjust- 130

ing said carrier in relation to one of said tracks comprising two separated fingers connected with said carrier and projecting on opposite sides of said latter track, an adjustable member connected with one of said fingers which engages one side of said track, and a pin fixed to the other finger and having an enlarged head which engages the other side of said track.
